ROLLER BIT

Elvin G. Boice, Houston, Tex., assignor to Reed
 Roller Bit Company, Houston, Tex., a corpora-
 tion of Texas

Application October 9, 1950, Serial No. 189,264

5 Claims. (Cl. 308—8.2)

1

This invention relates generally to roller bits for deep well drilling, and particularly to a roller bit having a new and improved bearing for the roller cutters thereof. Conventional roller bits for the drilling of oil wells include a bit head in which are mounted roller cutters provided with teeth to penetrate the formation when the head is rotated by the usual drill stem. During drilling operations, the bearing of the roller cutters are subjected to very great shocks and strains including destructive end thrusts. The bearings are also subjected to the abrasive action of mud-laden fluid which is pumped downwardly through the drill stem and bit and rises upwardly in the space between the drill stem and the wall of the well to keep the cutters cool, to remove the cuttings, and to perform other functions well-known to those skilled in the art.

This invention has for one of its objects to provide a roller bit with new and improved end thrust bearings, the parts of which may be quickly and easily assembled.

Other objects will hereinafter appear.

The preferred embodiments of the invention are illustrated by the accompanying drawings, in which

Fig. 1 is a fragmentary partly sectional view of a cross roller bit illustrating the use of one embodiment of the invention in the side roller cutter thereof; and

Fig. 2 is a sectional view (on a reduced scale) on the line 2—2 of Fig. 1.

Fig. 3 is another embodiment of the invention in the side roller cutter of the cross roller bit; and

Fig. 4 is a section (on a reduced scale) on the line 4—4 of Fig. 3.

Referring to Fig. 1, the lower portion of the cross roller bit head is indicated at 1, the cross roller cutter at 2 and the side roller cutter at 3. The head 1 is provided with a downwardly and inwardly inclined shaft 4 having a bore 5 for the reception of the pin 6 of the bridge 7, which pin is welded in place as indicated at 6-a. Between the shaft 4 and the side roller cutter 3 are load bearing rollers 7 and 8. The numeral 9 indicates my new and improved end thrust bearing rollers which in this embodiment are tapered substantially from end to end to bear against the inwardly tapered side walls 10 of the raceway of the shaft 4 and against the inwardly tapered side walls 11 of the raceway of the cutter 3, as shown by Fig. 1; and against each other as shown by Fig. 2. Within the shaft raceway defined by the tapered side walls 10 are a plurality of spring rings 12 which serve to yieldably urge the end

thrust bearing rollers 9 outwardly into their operative positions. The bearing rollers 9 are insertable into the raceways of the cutter 3 and shaft 4, defined by the walls 11 and 10, through an opening 14 against the resistance of the spring rings 12 which are normally of a diameter greater than that shown by Figs. 1 and 2 and which are compressed to a smaller diameter when the end thrust rollers 9 are thus inserted. After each 10 roller 9 is inserted through the opening 14 in the cutter against the resistance of the spring rings 12, it may be moved laterally in the raceways to make room for the roller to be inserted next. When all of the rollers 9 have been inserted the 15 parts are in the relative positions shown by Figs. 1 and 2. The opening 14 may be then closed by a plug 15 welded in place as indicated at 16.

In Figs. 3 and 4, the numerals 1 through 8 indicate parts similar to those shown by Figs. 1 and 2. In the embodiment shown by Figs. 3 and 4 however, the end thrust rollers 17 instead of being tapered substantially from end to end are provided with an inner tapered portion 17-a and an outer substantially cylindrical portion 17-b, and 25 the side walls 18 of the shaft 4 are inwardly tapered and the side walls 19 of the cutter 3 are substantially parallel so that the bearing rollers 17 bear against the said side walls 18 and 19 as shown by Fig. 3 and against each other as shown by Fig. 4. The opening in the cutter 3 through 30 which the bearing rollers 17 are insertable is indicated at 20 and the plug to close this opening at 21 welded as indicated at 22. The opening 20 is provided with a shoulder 20-a and the plug 21 with a reduced extension 21-a to fit the same. The 35 numeral 23 indicates spring rings corresponding with the spring rings 12 shown by Figs. 1 and 2.

It will be apparent from Figs. 1 and 2 that the end thrust bearing rollers 9 may be inserted through the opening 14 of the cutter into the raceways so that they will be in a position to rotate on axes substantially radial to the axis of rotation of the cutter 3.

It will also be apparent that when the rollers 9 are inserted through the openings 14 they will compress the spring rings 12 so that during the operation of the bit the spring rings 12 will yieldably urge the end thrust bearing rollers 9 outwardly into their operative positions.

It will also be apparent that the tapered end thrust bearing rollers 9 will roll upon the tapered side walls 10 of the shaft 4 and the tapered side walls 11 of the cutter 3, and that said tapered rollers 9 will roll upon each other and that this 55 will provide a good bearing between the rollers

and between the rollers and the walls of the raceways, to efficiently sustain the end thrust on the cutter 3.

The invention is not limited to the preferred embodiments herein disclosed. Various changes within the scope of the following claims will be apparent to those skilled in the art.

I claim:

1. A bit having a shaft; a roller cutter rotatable on said shaft; said shaft having a raceway with inwardly tapered side walls, said cutter having a raceway with inwardly tapered side walls, thrust bearing rollers in said raceways, rotatable on axes substantially radial to the axis of rotation of said cutter, and being tapered substantially from end to end to bear against each other and against the tapered side walls of said shaft raceway and said cutter raceway; a plurality of spring rings in said shaft raceway to urge said rollers outwardly into their operative positions; said cutter having an opening through which said rollers may be inserted to compress said rings and to occupy said raceways; means to close said opening after said bearing rollers are in place; and load sustaining bearings on each side of said thrust bearing rollers.

2. A bit having a shaft; a roller cutter rotatable on said shaft; said shaft having a raceway with inwardly tapered side walls, said cutter having a raceway with inwardly tapered side walls, thrust bearing rollers in said raceways, rotatable on axes substantially radial to the axis of rotation of said cutter, and being tapered substantially from end to end to bear against each other and against the tapered side walls of said shaft raceway and said cutter raceway; a plurality of spring rings in said shaft raceway to urge said rollers outwardly into their operative positions; said cutter having an opening through which said rollers may be inserted to compress said rings and to occupy said raceways; and means to close said opening after said bearing rollers are in place.

3. A bit having a shaft; a roller cutter rotatable on said shaft; said shaft having a raceway with inwardly tapered side walls, said cutter having a raceway with inwardly tapered side walls, thrust bearing rollers in said raceways, rotatable on axes

substantially radial to the axis of rotation of said cutter, and being tapered to bear against each other and against the tapered side walls of said shaft raceway and said cutter raceway; yieldable means in said shaft raceway to urge said rollers outwardly into their operative positions; said cutter having an opening through which said rollers may be inserted against the resistance of said yieldable means and to occupy said raceways; and means to close said opening after said bearing rollers are in place.

4. A bit having a shaft; a roller cutter rotatable on said shaft; said shaft having a raceway with inwardly tapered side walls, said cutter having a raceway with inwardly tapered side walls, thrust bearing rollers in said raceways, rotatable on axes substantially radial to the axis of rotation of said cutter, and being tapered to bear against each other and against the tapered side walls of said shaft raceway and said cutter raceway, said cutter having an opening through which said rollers may be inserted, and a plug to close said opening, said plug having a shoulder to position said plug in register with said cutter raceway.

5. A bit having a shaft, a roller cutter rotatable on said shaft, raceways in said shaft and cutter, thrust bearing rollers in said raceways and rotatable on axes substantially radial to the axis of said cutter, and means to yieldably urge said rollers into their operative positions in said raceways, said cutter having an opening, and said rollers being insertable through said opening into said raceways against the resistance of said yieldable means, and means to close said opening.

ELVIN G. BOICE.
